UNITED STATES PATENT OFFICE.

MERRILL M. WILCOX, OF SAGINAW, MICHIGAN, ASSIGNOR TO WILCOX MOTOR PARTS & MANUFACTURING CO., OF SAGINAW, MICHIGAN, A CORPORATION OF MICHIGAN.

TAPPET.

Continuation of application Serial No. 324,959, filed September 19, 1919. This application filed May 23, 1921. Serial No. 471,835.

To all whom it may concern:

Be it known that I, MERRILL M. WILCOX, a citizen of the United States, residing at Saginaw, in the county of Saginaw and 5 State of Michigan, have invented certain new and useful Improvements in Tappets; and I do hereby declare the following to be a full, clear, and exact description of the invention, such as will enable others skilled 10 in the art to which it appertains to make and use the same.

This invention relates to valve-actuating tappets for internal combustion engines, and pertains more particularly to certain 15 novel features of construction embodied in a valve tappet as a new article of manufacture, whereby I am enabled to produce an exceptionally light but strong tappet, with an enlarged base of very hard metal 20 such as case-hardened steel to contact with the engine cam, and an internally threaded plug in the opposite end of the tappet to receive the bolt or other adjustable device that contacts with the stem of the valve. 25 The arrangement of parts in my improved tappet construction is such that they can be easily, quickly and accurately assembled and the individual parts can be manufactured at small cost and by automatic machines of standard construction, 30 insuring uniformity of size and shape and weight.

With the foregoing and certain other objects in view, which will appear later in the 35 specification, my invention comprises the devices described and claimed and the equivalents thereof.

My invention is illustrated in the accompanying drawings, in which Fig. 1 is a central longitudinal section of a tappet.

Fig. 2 is a partial section of a tappet showing a means for holding the plug in place.

Fig. 3 is a side view of a modified form 45 of plug.

Fig. 4 is a part section of a tappet showing a still further modified means for securing the plug in the end of the tappet.

As is clearly shown in the drawings, the 50 tappet consists of the usual shell or body portion 1, which is preferably formed by boring a solid bar of metal from end to end to form a thin-walled tube; or the body may be formed of sheet metal rolled to the

form of a tube, or by drawing and pressing from a flat sheet of metal, or by using a short piece of tubing of proper diameter and thickness.

Secured to one end of the body 1 is a head member 2 formed of a separate piece 60 of metal, heat-treated and hardened. The head 2 may be formed with a laterally projecting flange, the face of the head being preferably ground for contact with the cam of the engine.

A projecting cylindrical shank may be formed on the head and accurately fitted to and preferably received in the bore of the body 1, to which it may be secured by spot welding, as in Fig. 1, or by any other practical or well-known means of securing cylindrical members in tubular members.

The broader aspects of my invention are described and claimed in my co-pending application, Serial No. 324,959, of which 75 this present application is a continuation.

The other end of the tubular body is provided with a plug or closure 3 threaded as at 4, adapted to receive a push rod not shown, against which the valve stem of the engine contacts in action. The closure 3 is preferably in the form of a plug, adapted to be received within the bore of the tubular body 1 and to be secured therein by any suitable means, as for example, by spot 85 welding.

To firmly seat the plug 3 in the body 1 at exactly the right vertical distance to suit the required overall length of the tappet, I preferably provide a shoulder 5 within 90 the body 1, the shoulder being formed by counter-boring. The shoulder acts as a stop to locate the plug properly and hold it in position when the tappet is being assembled.

The plug may be secured in place in the body 1 by threading and screwing it into the body, as shown at 6 in Fig. 2, or it may be externally recessed, as shown at 8 in Fig. 3, the metal of the body 1 being correspondingly pressed in to hold the plug in place. 100 In some cases I secure the plug in place by swaging over the upper edge 7 of the shell to form an inwardly projecting retaining flange.

Any or all of the above forms of plugs may in addition be spot welded in place if desired.

By the means above described, I have

produced a tappet of light weight and great strength. The parts are adapted to be easily and economically manufactured by automatic machinery and can be rapidly 5 and accurately assembled, either by semi-automatic machinery, or by hand.

The construction of plug 3, as shown in the drawings, is such as to enable the plug to be made of one piece of round bar that 10 can be cut with a minimum of waste, requiring no machine work to fit it to the counter bore and shoulder 5 of the tubular body 1.

Having thus described my invention, 15 what I claim and desire to secure by Letters Patent is:

1. As an article of manufacture, a tappet comprising a hollow tubular body, a hardened head having an elongated cylindrical 20 shank fixed to said body, the opposite end

of said body formed with an enlarged bore and an internal shoulder at the end of said bore, a cylindrical plug received entirely within said enlarged bore and abutting against said internal shoulder, said plug 25 fixed to said body, the outer end of said plug flush with the end of said tubular body.

2. As an article of manufacture, a tappet comprising a hollow tubular body, a cam-contacting head fixed to said body, the 30 opposite end of said tubular body formed within an enlarged bore and an internal shoulder at the end of said bore, a substantially cylindrical plug received entirely within said enlarged bore and abutting 35 against said internal shoulder, said plug fixed to said tubular body.

In testimony whereof, I affix my signature.

MERRILL M. WILCOX.
